UNITED STATES PATENT OFFICE

138,230

DESIGN FOR AN INFANT'S SUSPENSION BAR TOY

Eoina Nudelman, Chicago, Ill.

Application April 24, 1944, Serial No. 113,352

Term of patent 7 years

(Cl. D34—15)

To all whom it may concern:

Be it known that I, Eoina Nudelman, a citizen of France, residing at Chicago, in the county of Cook and State of Illinois, have invented a new, original, and ornamental Design for an Infant's Suspension Bar Toy, of which the following is a specification, reference being had to the accompanying drawing, forming part thereof.

Fig. 1 is a front elevational view of an infant's suspension bar toy, showing my new design; and Fig. 2 is a side view of the same.

The dominant feature of the design resides in the portions shown in full lines in the drawing.

I claim:

The ornamental design for an infant's suspension bar toy, as shown and described.

EOINA NUDELMAN.
